UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPEWRITING MACHINE.

Application filed November 12, 1920. Serial No. 423,531.

To all whom it may concern:

Be it known that I, CORNELIUS B. CORCORAN, a citizen of the United States, residing in borough of the Bronx, in the county 5 of the Bronx, city and State of New York, have invented certain new and useful Improvements in Typewriting Machines, of which the following is a specification.

This invention relates to ribbon-guiding 10 and directing mechanism for typewriters, more particularly for typewriters of the portable variety, and is here shown as applied to an Underwood standard portable typewriter.

15 In the above-mentioned portable typewriters, it is one of the important objects to reduce the height of the machine, necessitating lowering of the segment and also the lowering of the platen until (particularly in its 20 lower case-shift position) it is partly behind or below the level of the ends of the segment. The ribbon is lowered to a point below the ends of the segment, and the ribbon-cups are so located and arranged that the 25 ribbon passes in front of the ends of the segment. In order to avoid shortening of the type-bars, which would be necessary if the bars swung through 90 degrees, the bars are caused to swing through approximately 120 30 degrees. In traversing this large arc, the bars, especially those near the ends of the segment, tend to strike the ribbon lying in front of the ends of the segment, and their free movement is thus hindered. The ribbon 35 lies so low relatively to the segment that frequently actuation of the type-bars results in pressing the ribbon into the end segment slots.

40 This invention seeks to avoid the above-mentioned objectionable condition; first, by turning the slots in the ribbon-cups nearly 90 degrees, so that the ribbon leaves and enters the cups from the rearmost points, thus assisting or making it easier to direct 45 the ribbon to the rear of the segment, where it will be out of the path of the type-bars; second, by providing ribbon-guides to direct the ribbon to the rear of the segment; and, third, by providing guiding means in the 50 form of upstanding fingers which confine the ribbon in its rearward position at the rear of the segment.

Other features and advantages will hereinafter appear.

55 In the accompanying drawings,

Figure 1 is a plan view of a portable machine, showing the invention applied thereto, only such elements of the machine being shown as directly co-operate with the invention. 60

Figure 2 is a front elevation of the device shown in Figure 1.

The standard portable typewriter is shown as comprising a frame indicated generally by the numeral 1, and has a carriage provided with a platen 2 and mounted on a rail 3 and adapted to travel from right to left by letter-space movements upon actuation of type-bars 4. Attached to the rail is a support 5 having upper arms 6 acting as 70 guides for ribbon-supporters 7 which form guiding means for the ribbon adjacent the printing point on the platen. The usual segment 10, provided with slots 11 in which operate the type-bars 4, is fixed to the frame 75 of the machine and rigidly supports the type-guide 12 by means of the bracket portion 13 of said guide. It is understood that the rail 3 and the mechanism which it supports shifts vertically when the carriage is 80 shifted, in the usual case-shift operation.

On the shift-frame of the machine (which includes the rail 3) are suitably mounted, at the front of the ends of the platen 2 and forward and laterally outward from the ends of 85 the type-bar segment 10, ribbon-cups 15 provided, at the front thereof, with openings 17 and carrying ribbon-spools 16. Ordinarily, the cups are mounted so that the ribbon is fed out of one cup and into the other at points 90 approximately on a line joining their centers, as shown by the dot-and-dash line in Figure 1. It can here be seen that the ribbon in such a case would be led in front of the segment, and since the entire machine 95 is built low, the upper ends of the segment and the accompanying type-bar slots are above the level of the ribbon spools and of the lower part of the platen and are behind the ribbon, as will be clear from an inspection of Figure 2. The result is that the end type-bars, when operated, particularly in the lower case-shift position of the platen and other parts carried by the shift-frame will tend to force the ribbon into the end-slots 100 105 and impair the operation of the machine. To remedy this defect, the present invention provides means for guiding and directing the ribbon to the rear of the segment.

To this end, the ribbon-cups 15 are turned 110

through an angle of approximately 90 degrees, bringing the openings 17 directly in the rear. The detached portions 20 of the cups project at the rear of the cups and are 5 formed into bearings for shafts 21 of ribbon-guiding rollers 22, around which the ribbon passes. It will be seen that the ribbon-guides 22 are located sufficiently to the rear so that the ribbon is fed out towards the 10 rear of the segment. To guide the ribbon in this location and prevent it from slipping over the segment, there are fastened to the rail 3 at 25 two upstanding fingers 26 bent outwardly at 27 and having downturned ribbon-guiding ends 28 rearward from and adjacent to the ends of the type-bar segment 10. 15

It is readily seen that although the first ribbon-guides or guide rollers 22 and the second ribbon-guides or upstanding fingers 20 20 26 are features adapted to be used together, the up-standing fingers 26 can be used alone with a machine provided with ordinary ribbon-cups, and thus act as a guide to direct the ribbon toward the rear of the segment. 25

It can also be seen from Figure 1 that the turning of the cups in the manner shown and the provision of the guides 22 would alone suffice to direct the ribbon toward the rear of the segment, even if there were 30 no upstanding fingers. However, the two ribbon-guides 22 and 28 co-operate and are combined with the other parts and features of the machine in such manner as effectively to maintain the ribbon out of the path of 35 the type-bars at the front of the type-bar segment.

Variations may be resorted to within the scope of the invention, and portions of the improvements may be used without others. 40

Having thus described my invention, I claim:

1. In a front-strike typewriting machine, the combination with a platen, a type-bar segment forward from the platen and extending at its ends to a level above the lower part of the platen, type-bars pivoted on the type-bar segment, ribbon-spools at the front of the ends of the platen forward and laterally outward from the ends of the type-bar segment, and guiding means for the ribbon adjacent the printing point on the platen, said spools and guiding means being at levels so that the ribbon between the spools and guiding means is below the ends of the type-bar segment, of ribbon-guides between 50 said guiding means and spools for directing the ribbon to the rear of the type-bar segment, whereby the ribbon will be out of the path of the type-bars. 55

2. In a front-strike typewriting machine, the combination with a platen, a type-bar segment forward from the platen and extending at its ends to a level above the lower part of the platen, type-bars pivoted 60 on the type-bar segment, ribbon-spools at

the front of the ends of the platen forward and laterally outward from the ends of the type-bar segment, and guiding means for the ribbon adjacent the printing point on the platen, said spools and guiding means 70 being at levels so that the ribbon between the spools and the guiding means is below the ends of the type-bar segment, of ribbon-guides rearward from the spools and laterally outward from and below the level 75 of the ends of the type-bar segment, for directing to the rear of the ends of the type-bar segment the parts of the ribbon which extend between said ribbon-guides and said guiding means adjacent the printing point, so the ribbon will be out of the path of 80 the type-bars. 85

3. In a front-strike typewriting machine, the combination with a platen, a type-bar segment forward from the platen and extending at its ends to a level above the lower part of the platen, type-bars pivoted on the type-bar segment, ribbon-spools at the front of the ends of the platen forward and laterally outward from the ends of the type-bar segment, ribbon-cups containing the ribbon-spools, and guiding means for the ribbon adjacent the printing point on the platen, said spools and guiding means being at levels so that the ribbon between 90 the spools and the guiding means is below the ends of the type-bar segment, of ribbon-guides carried by the ribbon-cups sufficiently to the rear thereof so that the parts of the ribbon which extend between said ribbon-guides and said guiding means adjacent the printing point will pass to the rear of the ends of the type-bar segment, so as to be out of the path of the type-bars. 95

4. In a front-strike typewriting machine, the combination with a platen, a type-bar segment forward from the platen and extending at its ends to a level above the lower part of the platen, type-bars pivoted on the type-bar segment, and ribbon-spools at the front of the ends of the platen forward and laterally outward from the ends of the type-bar segment and occupying a level below the level of the ends of the type-bar segment, of ribbon-guides rearward from and adjacent to the ends of the type-bar segment to prevent the ribbon passing in front of the type-bar segment, whereby the ribbon is guided out of the path of the type-bars. 110 115 120

5. In a front-strike typewriting machine, the combination with a platen, a type-bar segment forward from the platen and extending at its ends to a level above the lower part of the platen, type-bars pivoted on the type-bar segment, ribbon-spools at the front of the ends of the platen forward and laterally outward from the ends of the type-bar segment, and guiding means for the ribbon adjacent the printing point, said spools 125 130

and guiding means being at such low levels that the ends of the type-bar segment extend above the level of the ribbon between the spools and said guiding means, of a first 5 ribbon-guide at the rear of each spool between the spool and the platen and laterally outward from and below the level of the adjacent ends of the type-bar segment for directing the ribbon to the rear of the 10 type-bar segment, and a second ribbon-guide between each said first ribbon-guide and said guiding means adjacent the printing point to maintain the ribbon at the rear of the ends of the type-bar segment, whereby said ribbon-guides will maintain 15 the ribbon out of the path of the type-bars at the front of the type-bar segment.

CORNELIUS B. CORCORAN.
